CLAIM

The ornamental design for a remote control cover, as shown and described.

DESCRIPTION

FIG. 1 is a top view of a remote control cover showing my new design;

FIG. 2 is a bottom view thereof;

FIG. 3 is a front view thereof;

FIG. 4 is a rear view thereof;

FIG. 5 is a left side view thereof;

FIG. 6 is a right side view thereof;

FIG. 7 is a top perspective view thereof;

FIG. 8 is a bottom perspective view thereof;

FIG. 9 is a cross-sectional view thereof taken along lines 9-9 shown in FIG. 1; and,

FIG. 10 is a cross-sectional view thereof taken along lines 10-10 shown in FIG. 1.

The broken lines in the figures depict portions of the remote control cover that form no part of the claimed design.

1 Claim, 7 Drawing Sheets
